UNITED STATES PATENT OFFICE

2,152,274

STENCIL ATTACHMENT FOR SPRAY GUNS

Martin S. Papazian, Worcester, Mass.

Application August 26, 1936, Serial No. 98,029

7 Claims. (Cl. 101—114)

This invention relates to means adapted to facilitate the use of a stencil or similar marking means with a spray gun.

Difficulty has been experienced in effectively numbering or marking billets or other hard surface objects so that a permanent mark is obtained. The usual present day practice is to mark them by the use of a steel die. However, the impression made by the die is both small and shallow so that it is rendered illegible by rust.

The object of this invention is to provide stencil means adapted for use with an ordinary spray gun, whereby billets and the like may be quickly and effectively marked with stenciled identifications.

The above and other objects will be apparent as the description proceeds and by reference to the accompanying drawing, in which:

Figure 1 is an elevation, partly in section, of one embodiment of my invention.

Figure 2 is a cross-section and plan taken on line II—II of Figure 1.

In the particular embodiment of my invention illustrated in the accompanying drawing the numeral 2 indicates a standard spray gun. The gun 2 receives compressed air through a tube 4 and paint through a tube 6. The tubes 4 and 6 are held together by clamps 10 and 11 and can be used as handles for the gun 2. The tubes 4 and 6 are connected to sources (not shown) of air and paint, respectively, by suitable lengths of flexible conduit (not shown) so that the gun 2 can be placed in any desired position. Couplings 8 connect the tubes 4 and 6 to the gun 2 in order to allow the gun 2 to be readily removed from the tubes 4 and 6 so that the gun 2 can be cleaned or replaced.

The gun 2 is a standard spray gun and has standard equipment including a spray control 14, a handle 16, a trigger 18 and a nozzle 20. In operation, of course, when the trigger 18 is pulled towards the gun 2 a blast of air, carrying paint, is projected out of the nozzle 20. The spray control 14 should be set so that the air expanding through the nozzle 20 is rich in paint in order that only a small volume of air need be expelled to coat the exposed surface with paint.

The gun 2 has a plate 24, preferably rectangular, welded to it between the nozzle 20 and the handle 16. The plate 24 has apertures 25 spaced around its periphery. A hood 26 made of sheet or other light metal and resembling a frustum of a rectangular pyramid is carried by the gun 2. The hood 26 has integral inwardly extending right angle flanges on its upper end. The flanges of

the hood 26 have tapped apertures 27 therethrough which align with the apertures 25 when the gun 2 is placed upon the hood 26 so that screws 28 can be placed in the apertures 25 and screwed into the apertures 27 to secure the hood 26 to the plate 24.

A cowl 30 is welded to the inside of the hood 26 and extends upwardly therefrom. The cowl 30 fits closely around the nozzle 20 and protects it from being fouled by paint dust confined in the hood 26. It will be appreciated that the hood 26 can be of any desired shape or length so long as it is adapted to be removably secured to the plate 24.

A plate 32 having apertures 34 therethrough fits in the bottom of the hood 26 and is secured to it by any convenient, quickly releasable, means such as hooks 35. The apertures 34 and plate 32 can be designed to act as a stencil, or the apertures 34 can receive stencils 36 therein. It is preferable, however, to have changeable stencils which fit in the plate 32 in place of a variety of plates which have different shaped apertures therethrough, but whichever form is deemed convenient can be used. The stencils 36 may be wedged or fastened in the apertures 34, but preferably merely rest on the plate 32 by means of supporting flanges. This facilitates changing the stencils 36 so that any desired stencil can readily be placed in the plate 32.

For automatically operating the apparatus an extension arm 40 is welded or otherwise secured to the trigger 18 so that when the hood 26 is placed down against the object to be marked the arm 40 strikes the object to be marked and operates the trigger 18. If the object to be marked is not large enough or of the proper shape to engage the arm 40 means, such as a horizontal plate, may be fixed adjacent the apparatus to engage the arm 40 when the hood 26 is in its proper position.

The apparatus is particularly adapted for marking billets or ingots and can be operated in any desired position. If the billets are lying on the floor the stenciling apparatus can readily be moved around in order to mark the billets or, if they are passing along on a conveyer the spraying apparatus can be positioned in one place and rapidly mark them as they pass by.

It will be appreciated that the invention is not limited to the specific form illustrated and described but is actually defined in the appended claims.

I claim:

1. In combination with a spray gun, a nozzle

- on said gun, a plate secured to said gun behind said nozzle and extending at substantially right angles to said nozzle, a sheet metal hood substantially frusto-pyramidal in shape removably secured at its smaller end to said plate, a cowl secured to the inside of said hood and receiving the nozzle therethrough, a stencil carried by said hood and being removable therefrom, and means for automatically operating said gun when said hood is placed against a body to be marked.
2. In combination with a spray gun, a nozzle on said gun, a plate secured to said gun, a sheet metal hood substantially frusto-pyramidal in shape removably secured at its smaller end to said plate, a cowl secured to the inside of said hood and receiving the nozzle therethrough, a stencil carried by said hood and being removable therefrom, and means for automatically operating said gun when said hood is adjacent a body to be marked.
3. In combination with a spray gun, a nozzle on said gun, a plate secured to said gun, a hood removably secured to said plate, a cowl secured to the inside of said hood and receiving the nozzle therethrough, a stencil carried by said hood, and means for automatically operating said gun when said hood is adjacent a body to be marked.
4. In combination with a spray gun, a nozzle associated with said gun, a hood removably carried by and extending from said nozzle, a stencil associated with the extended end of said hood, said hood having means associated therewith to prevent fouling of said nozzle by the spraying medium, and a trigger carried by said gun, said

trigger having an extension arm thereon, said extension arm adapted to be depressed by the object to be stenciled to actuate said trigger when the stencil is placed adjacent the object.

5. In combination with a spray gun, a nozzle on said gun, means for removably attaching a sheet metal hood to said gun, a cowl secured to the inside of said hood and receiving the nozzle therethrough, a stencil plate, quickly removable means for securing said stencil plate to the end of said hood, means carried by said plate for receiving stencils and means for automatically operating said gun when said stencil plate is placed against a body to be marked.

6. In combination with a spray gun, a nozzle on said gun, a sheet metal hood, means for removably attaching said hood to said gun, a stencil plate, a plurality of hook portions carried by said stencil plate adapted to cooperate with the end of said hood to removably hold said stencil plate on the end thereof, means carried by said plate for receiving stencils, and means for automatically operating said gun when said stencil plate is placed against an object to be marked.

7. In combination with a spray gun, a nozzle on said gun, a sheet metal hood substantially frusto-pyramidal in shape removably secured to said gun at its smaller end, a cowl secured to said hood and receiving the nozzle therethrough, a stencil-plate, quickly releasable means for securing said stencil plate to the larger end of said hood, means carried by said plate for receiving stencils, and means for automatically operating said gun when said plate is placed against an object to be marked.

MARTIN S. PAPAZIAN.
